UNITED STATES PATENT OFFICE.

LUDVIG S. IPSEN, OF MALDEN, MASSACHUSETTS, ASSIGNOR TO AMERICAN TYPE FOUNDERS COMPANY, OF NEW YORK, N. Y., A CORPORATION OF NEW JERSEY.

DESIGN FOR A FONT OF TYPE.

SPECIFICATION forming part of Design No. 36,367, dated June 16, 1903.

Application filed April 29, 1903. Serial No. 154,900. Term of patent 14 years.

To all whom it may concern:

Be it known that I, LUDVIG S. IPSEN, of Malden, county of Middlesex and State of Massachusetts, have invented a new, original, and ornamental Design for a Font of Type, of which the following is a specification.

The design is shown in the accompanying drawing, from which it will be seen that the font comprises capital and small letters, the usual set of numerals, and the sign for "and," and the dollar and pounds-sterling signs.

What I claim as my invention is—
The ornamental design for a font of type as shown.

In testimony whereof I hereunto set my name this 31st day of March, 1903.

LUDVIG S. IPSEN.
